UNITED STATES PATENT OFFICE.

ALEXANDRE G. LAURENT, OF ST. PETERSBURG, RUSSIA.

HAND FIRE-EXTINGUISHING APPARATUS.

No. 858,188.

Specification of Letters Patent.

Patented June 25, 1907.

Application filed September 22, 1906. Serial No. 335,718.

To all whom it may concern:

Be it known that I, ALEXANDRE G. LAURENT, a subject of Russia, residing at St. Petersburg, Russia, have invented new and 5 useful Improvements in Hand Fire-Extinguishing Apparatus, of which the following is a specification.

This invention has for its object to provide a hand fire extinguishing apparatus of the 10 kind in which two or more liquids, arranged separately in a common container, are caused to mingle in the case of fire so that they generate gases (carbonic acid) which expel the liquids in a powerful jet.

15 In the appliances of this kind hitherto employed, when the appliance was utilized, the two or more liquids have been completely mixed one with the other, so that the pressure within the container became relatively high 20 and it was consequently necessary to make the container strong. Further it was also impossible to stop the jet before the apparatus was emptied, even when its use became no longer necessary, so that the appliance 25 had to be recharged after use on every occasion before it was possible to use it again.

The defects are obviated by means of the 30 present invention, owing to the fact that it sprays foam instead of liquid. The weight 35 of this foam being from 8 to 10 times lighter than water, a jet of foam from 6 to 8 meters high can be produced with a pressure of but one atmosphere, and the container may therefore be formed from ordinary tin or 40 galvanized iron by soldering. In addition to this, the mixture of the two or more liquids forming the foam takes place in such a manner that only the quantities required for the formation of a certain quantity of foam are 45 mixed together, and further mixing takes place gradually as this foam is sprayed out. As a result of this, the operation of the appliance may be caused to cease at any moment, and it may be re-started at any time as long 50 as the apparatus contains any of the liquids.

The formation of the foam is produced by adding to one of the liquids (or to both of them) any appropriate viscous foam-forming substance. There are many such substances, 55 but the most adyantageous is extract of liquorice root (*succus liquoritæ*).

Various forms of the invention are illustrated by way of example in the accompanying drawing, in which:

55 Figure 1 represents a vertical section through a fire extinguisher embodying the

invention. Figs. 2 and 3 are respectively a vertical and a horizontal section of a modified form of the apparatus, and Figs. 4 and 5 are respectively a vertical and a horizontal 60 section of a further modification of the apparatus.

The fire extinguisher (Fig. 1) consists of a cylindrical reservoir *b* in which another reservoir *a* of acid-proof material is placed, its upper part being inclosed by a conical partition *c* soldered to the wall of the reservoir *b*. Between the upper edge of the partition and the mouth of the container *a* there exists a relatively narrow opening which opens into an 70 upper mixing chamber *d* in which the two liquids are gradually mixed together and there produce the foam. The mixing chamber *d* is provided with a spraying nozzle *e* and is closed above by a mechanically fixed plug 75 *h*. Any ordinary plug may however be employed for this purpose, as the pressure existing inside the apparatus is not sufficiently strong to force the plug out. The apparatus is provided with handles *g*. 80

The container *b* may be charged with a soda solution and the container *a* with a dilute acid, the quantity of acid employed and the quantity of lye contained in the vessel *b* (bicarbonate of sodium for example) corresponding 85 one with the other. The viscous, foam-producing substance is added to one of these liquids, and may consist for example of extract of liquorice root which is added in a quantity from .05 to .5% of the weight of the 90 liquids contained in the two vessels *a* and *b*.

If the apparatus is to be employed for extinguishing burning liquids, such as petroleum, oil, naphtha, benzin or the like, a thin readily-flowing foam containing 0.05% of extract 95 of liquorice root is necessary, while for extinguishing burning wood and other horizontal and vertical services, it is necessary to employ a denser foam, for which up to 5% of extract of liquorice root must be added 100 to the liquids in the vessels.

When it is desired to use the apparatus, it is inverted or tilted, so that a portion of the liquid in the vessels *a* and *b* flows into the mixing chamber *d*. When the two liquids 105 mix, a foam is formed, owing to the liberation of carbonic acid and the presence of the foam-producing substance, the volume of this foam exceeding that of the liquid many times, say from 8 to 10 times. The formation of the foam in the mixing chamber *d* produces the following results, owing to the 110

increase of volume and the increase of pressure thereby obtained; in the first place, the pressure forcing the two liquids toward the openings of the vessels *a* and *b* is equalized; 5 in the second place, owing to the pressure in the chamber *d*, the compact foam stops the openings of the vessels *a* and *b*, so that the liquids can no longer leave them, and in the third place, owing to this internal pressure, 10 the foam is ejected in the form of a jet out of the opened lateral nozzle *e*. As soon, however, as a portion of the foam has been ejected through the aperture *e*, the internal pressure in the chamber *d* diminishes, the 15 equilibrium between the vessels *a*, *b* and *d* is disturbed so that the liquids in the vessels *a* and *b* can again partially leave the vessels, and a fresh formation of foam takes place, and so on in succession. In this manner the 20 two liquids are gradually and intermittently poured out of the vessels *a* and *b*, and the foam thereby formed is ejected through the nozzle *e*. If the vessel is again placed upright upon its bottom, so that the orifices of 25 the two vessels *a* and *b* are directed upward, the formation of foam ceases, as the two liquids are no longer able to mingle. If, however, the apparatus is again inverted or tilted, it begins to work as vigorously as before, and this action continues as long as any liquid remains in the two vessels. The pressure in the chamber *d* does not exceed one atmosphere when the discharge orifice is open. When the discharge orifice is closed 30 or accidentally stopped, the pressure is not higher than two atmospheres; as above stated the apparatus therefore presents no danger of explosion even if made by soldering ordinary tin or galvanized iron.

35 The modified form of the apparatus illustrated in Figs. 2 and 3 differs from that described above, in that the formation of the foam is not produced by completely inverting the apparatus, but merely by inclining it as far as the horizontal position.

In the form represented in Figs. 4 and 5 the vessel *b* is divided into two compartments by means of a vertical partition *l*; one of these compartments serving for the reception of the vessel *a* containing the acid, while the other is charged with a soda solution.

It will of course be understood that the apparatus may be modified in many other ways without departing from the principle of the invention.

Having thus described my invention, what I claim is:

1. A fire-extinguishing apparatus, comprising a receptacle containing separated gas-producing fire-extinguishing substances and a foam-producing substance which causes the substances to produce a gas-filled foam simultaneously with the evolution of gases. 60

2. A fire-extinguishing apparatus, comprising a receptacle containing separated gas-producing fire-extinguishing substances and a foam-producing substance and having a mixing chamber in which the substances, when mingled, produce a gas-filled foam simultaneously with the evolution of gases. 70

3. A fire-extinguishing apparatus, comprising a receptacle containing separated gas-producing fire-extinguishing substances and a foam-producing substance mixed with one of said fire-extinguishing substances to cause a gas-filled foam to be produced simultaneously with the evolution of gases. 75

4. A fire-extinguishing apparatus, comprising a receptacle containing separated gas-producing fire-extinguishing substances and a foam-producing substance mixed with said fire-extinguishing substances to cause a gas-filled foam to be produced simultaneously with the evolution of gases. 80

5. A fire-extinguishing apparatus, comprising a receptacle having a nozzle and a mixing chamber, and containing separated gas-producing fire-extinguishing substances and a foam-producing substance mixed with one of the fire-extinguishing substances to cause a gas-filled foam to be produced simultaneously with the evolution of gases. 85

6. A fire-extinguishing apparatus, comprising a receptacle containing separated gas-producing fire-extinguishing substances and an extract of licorice root (*succus liquoritæ*) which is mixed with one of said substances to produce a gas-filled foam simultaneously with the evolution of gases. 90

7. A fire-extinguishing apparatus, comprising a receptacle containing a mixing chamber with a nozzle and compartments having narrow discharge openings into the mixing chamber and holding gas-producing fire-extinguishing substances and a foam-producing substance causing the substances to produce a gas-filled foam simultaneously with the evolution of gases. 100

In testimony whereof I have signed my name to this specification in the presence of two subscribing witnesses.

ALEXANDRE G. LAURENT.
